FOUNTAIN PEN

Clinton E. Marshall, Bronx, N. Y.

Application December 31, 1942, Serial No. 470,877

17 Claims. (Cl. 120—43)

This invention relates to pens and similar writing implements. More particularly, the invention relates to a penpoint and feed for use in fountain pens wherein the penpoint is formed from clear or colored glass. The novel features of the invention will be best understood from the following description when taken together with the accompanying drawing, in which certain embodiments of the invention are disclosed, and in which the separate parts are designated by suitable reference characters in each of the views; and in which:

Fig. 1 is a diagrammatic sectional view of the writing end portion of a fountain pen, showing a penpoint and feed in elevation.

Fig. 2 is a top plan view of the penpoint or nib.

Fig. 3 is a bottom plan view of the structure shown in Fig. 2.

Fig. 4 is a top plan view of the feed shown in Fig. 1.

Fig. 5 is a longitudinal sectional view through a penpoint and feed, showing a modification.

Fig. 6 is a bottom plan view of the penpoint shown in Fig. 5.

Fig. 7 is a view similar to Fig. 5, showing a modification.

Fig. 8 is a plan view of the feed, as shown in Fig. 7, and

Fig. 9 is a bottom plan view of the tip end portion of a penpoint or nib, showing another modification.

In the construction of penpoints or nibs, particularly as used in fountain pens, it has been a common practice to employ various types and kinds of metals or combination of metals, particularly with respect to the tip ends of such pens in producing the desired results and to care for the wear to which the penpoint is subjected.

It is the purpose of my invention to provide a penpoint or nib which is entirely composed of glass, thus providing a penpoint or nib which will have the required hardness and also possess the property of providing free flow of ink, and also eliminating any possible corrosion or deterioration of a metal as is commonly experienced with other types of metal pens.

My invention also comprises the use of a feed in conjunction with the penpoint which may also be composed of glass or suitable plastic material. In both instances, that is to say, both the penpoint and the feed are made substantially half round in cross section so that collectively, these members may be made to fit snugly

within the feed section of the fountain pen and may be quickly and easily removed therefrom.

In Fig. 1 of the drawing I have diagrammatically illustrated at 10 a part of the feed section 5 of a fountain pen, in the bore 11 of which is frictionally supported a penpoint or nib 12 and a feed 13.

The nib 12, as seen in Figs. 1 to 3 inclusive comprises an elongated half round strip of glass, 10 the lower surface 14 of which is flat, and has at the outer end portion thereof an elongated feed groove 15 which terminates at the writing end 16 of the nib. The point of the nib is formed by bevelling the side walls as seen at 11 to form 15 the point 16 and also by an abrupt bevel 18 at the top of the nib which joins the rounded contour in a slightly bevelled portion 19.

The pointed end 16 may be rounded to provide the desired writing surface, and as seen in Fig. 20 9, the feed groove 20, which is equivalent to the groove 15 may be contracted at the pointed end 21 of the nib, as seen at 22, particularly where it is desirable to form a finer writing point. At this time it will be understood that 25 the illustrations in the accompanying drawing are more or less diagrammatic for sake of clarity, but in all cases, the required feed groove and point construction will be provided.

In the construction shown in Figs. 1 and 4, 20 the feed 13 is provided with a feed groove 23, which extends from the inner end 24 of the feed to a point 25 short of the contracted end 26 of this feed. The contracted end is formed by bevelled side walls 27 and a bevelled end wall 28. 35 It will be understood that the feed 13 may be adjusted to different positions longitudinally with respect to the nib 12 in setting the end 26 to the desired position with respect to the point 16 at all times. However, necessary clearance 40 will be provided for free exposure of the point to the surface over which the pen is moved.

The penpoint or nib is also preferably provided with means for venting the pen and to this end a vent passage 29 is provided on the 45 surface 14 which opens through the inner end of the pen in a groove 30 and outwardly to atmosphere beyond the section 10 through a groove 31 which joins the chamber 29 through a port 32.

In Figs. 5 and 6 of the drawing is shown a 50 slight modification of the structure shown in Figs. 1 to 4 inclusive in which the feed section 13 is the same as that employed in the other figures, but the nib 33 differs from the nib 12 in that a well portion or chamber 34 is formed in the feed groove 35 inwardly of the pointed end

36 of the nib, but in position to register with the end 25 of the groove 23 of the feed.

In Figs. 7 and 8 of the drawing is shown another modification wherein a nib similar to the nib 33 is employed, and substituted for the feed 13 is a feed 31, the groove 38 of which terminates at its outer end in a well or chamber 39 similar to the chamber 34, and registering or substantially registering therewith, depending upon the adjustment of the feed with respect to the nib.

The purpose of the well or storage chambers 34, 39, is to provide at the pointed end portion of the penpoint or nib a fairly large supply of ink which will deliver the ink more freely to the writing point, particularly with some types and kinds of inks, and with penpoints of the finer writing points.

In the structure shown in Figs. 5 to 7, the penpoint or nib 33 also has an air vent chamber 40, similar to the chamber 29 which opens through the inner end of the nib in a groove 41 and to a groove 42 on the top surface of the nib through a port or passage 43.

The port 43 is preferably arranged at an angle, as clearly illustrated in Figs. 5 and 7 in order to prevent discharge of ink particularly in the agitation of the pen. While the venting has been illustrated as part of the nib construction, it will be apparent that the same general structure is applicable to the feed for accomplishing the same results.

Having fully described my invention, what I claim as new and desire to secure by Letters Patent is:

1. In writing implements of the class described, a pen-point comprising an elongated half round body of glass, one end of said body being bevelled to form a writing point at the flat surface of said body, said flat surface having an ink feed groove extending to said point, said ink feed groove terminating short of the other end of said body, and means arranged on the flat surface of said body for feeding ink from a source of supply to the feed groove of said body.

2. In writing implements of the class described, a pen-point comprising an elongated half round body of glass, one end of said body being bevelled to form a writing point at the flat surface of said body, said flat surface having an ink feed groove extending to said point, said ink feed groove terminating short of the other end of said body, means arranged on the flat surface of said body for feeding ink from a source of supply to the feed groove of said body, and said body having a large chamber registering with the feed groove adjacent the pointed end of said body.

3. In writing implements of the class described, a pen point comprising an elongated body half round in cross section throughout the major portion of its length, said body presenting a flat surface and a convex surface, the convex surface at one end of the body being bevelled to form a writing point terminating at the flat surface of said body, and said flat surface having an ink feed groove arranged longitudinally thereof and extending to said point.

4. A pen point for writing implements, comprising an elongated body composed entirely of glass, said body having a flat surface extending throughout the length thereof and a convex surface, one end of said body being shaped to form a writing point terminating at the flat surface

of said body, and the flat surface of said body having means extending longitudinally thereof for feeding ink to said point.

5. A pen point for writing implements, comprising an elongated body composed entirely of glass, said body having a flat surface extending throughout the length thereof and a convex surface, one end of said body being shaped to form a writing point terminating at the flat surface 10 of said body, the flat surface of said body having means extending longitudinally thereof for feeding ink to said point, and a feed member arranged directly upon and extending longitudinally of the flat surface of said body and having means cooperating with said first named means in controlling feed to the point of said body.

6. A pen point for writing implements, comprising an elongated body composed entirely of glass, 20 said body having a flat surface extending throughout the length thereof and a convex surface, one end of said body being shaped to form a writing point terminating at the flat surface of said body, the flat surface of said body having means extending longitudinally thereof for feeding ink to said point, a feed member arranged directly upon and extending longitudinally of the flat surface of said body and having means cooperating with said first named means in controlling feed to the point of said body, and means for venting the ink flow to said first named means and member.

7. A pen point for writing implements, comprising an elongated body composed entirely of glass, 30 said body having a flat surface extending throughout the length thereof and a convex surface, one end of said body being shaped to form a writing point terminating at the flat surface of said body, the flat surface of said body having means extending longitudinally thereof for feeding ink to said point, a feed member arranged directly upon and extending longitudinally of the flat surface of said body and having means cooperating with said first named means in controlling feed to the point of said body, means for venting the ink flow to said first named means and member, and means forming a large ink storage chamber inwardly of and adjacent said writing point.

8. A pen point for writing implements, comprising an elongated nib having a flat surface extending throughout the length thereof, one end of the nib being contracted to form a writing point, the flat surface of said nib having a groove 45 extending longitudinally thereof and extending to said point, and means arranged upon the flat surface of said nib for feeding ink from the other end of the nib to said groove.

9. A pen point for writing implements, comprising an elongated nib having a flat surface 50 extending throughout the length thereof, one end of the nib being contracted to form a writing point, the flat surface of said nib having a groove extending longitudinally thereof and extending to said point, means arranged upon the flat surface of said nib for feeding ink from the other end of the nib to said groove, and said nib and last named means collectively forming an ink storage chamber registering with said groove and arranged adjacent the pointed end of said nib.

10. A pen point for writing implements, comprising an elongated nib having a flat surface 75 extending throughout the length thereof, one end of the nib being contracted to form a writing point, the flat surface of said nib having a groove

extending longitudinally thereof and extending to said point, means arranged upon the flat surface of said nib for feeding ink from the other end of the nib to said groove, said nib and last named means collectively forming an ink storage chamber registering with said groove and arranged adjacent the pointed end of said nib, and means for venting the ink supply to said nib.

11. A pen point for writing implements, comprising an elongated nib having a flat surface extending throughout the length thereof, one end of the nib being contracted to form a writing point, the flat surface of said nib having a groove extending longitudinally thereof and extending to said point, means arranged upon the flat surface of said nib for feeding ink from the other end of the nib to said groove, said nib and last named means collectively forming an ink storage chamber registering with said groove and arranged adjacent the pointed end of said nib, means for venting the ink supply to said nib, and said last named means comprising an air chamber formed on the nib and a passage extending from said chamber to a point on the nib beyond the mounting end portion thereof for exposure to atmosphere beyond the limits of the writing implement.

12. The combination with a fountain pen, of a nib and feed member, said nib and member having substantially flat engaging surfaces extending longitudinally thereof, the nib having a contracted writing end, the corresponding end of said member being bevelled and terminating short of the writing end of said nib, said surface of the member having an ink feed groove extending substantially the full length thereof and terminating short of said bevelled end, and said nib having an ink feed groove at the writing end portion only thereof and registering with the groove of said member.

13. The combination with a fountain pen, of a nib and feed member, said nib and member having substantially flat engaging surfaces extending longitudinally thereof, the nib having a contracted writing end, the corresponding end of said member being bevelled and terminating short of the writing end of said nib, said surface of the member having an ink feed groove extending substantially the full length thereof and terminating short of said bevelled end, said nib having an ink feed groove at the writing end portion only thereof and registering with the groove of said member, and the grooved portion of said nib having an enlarged chamber adjacent the writing end thereof.

14. The combination with a fountain pen, of a nib and feed member, said nib and member having substantially flat engaging surfaces extending longitudinally thereof, the nib having a contracted writing end, the corresponding end of said member being bevelled and terminating short of the writing end of said nib, said surface of the member having an ink feed groove extending substantially the full length thereof and terminating short of said bevelled end, said nib having an ink feed groove at the writing end portion only thereof and registering with the groove of said member, and said nib and member collectively forming a large chamber registering with the grooves of said nib and member and arranged adjacent the writing end of said nib.

15. The combination with a fountain pen, of a nib and feed member, said nib and member having substantially flat engaging surfaces extending longitudinally thereof, the nib having a contracted writing end, the corresponding end of said member being bevelled and terminating short of the writing end of said nib, said surface of the member having an ink feed groove extending substantially the full length thereof and terminating short of said bevelled end, said nib having an ink feed groove at the writing end portion only thereof and registering with the groove of said member, and means forming an air vent for the grooves of said nib and member.

16. A pen point comprising an elongated glass body having a flat surface throughout the major portion of the length thereof, one end of said body being contracted to form a writing point terminating at said flat surface, said flat surface of the body being grooved to provide an ink feed extending to the writing point, a member mounted on said body and extending longitudinally thereof, and said member having means for feeding ink to the grooved portion of said body.

17. A pen point comprising an elongated glass body having a flat surface throughout the major portion of the length thereof, one end of said body being contracted to form a writing point terminating at said flat surface, said flat surface of the body being grooved to provide an ink feed extending to the writing point, a member mounted on said body and extending longitudinally thereof, said member having means for feeding ink to the grooved portion of said body, and said member and body collectively forming a large ink storage chamber inwardly of and adjacent the writing point of said body.
